UNITED STATES PATENT OFFICE

168,326

AUTOMOBILE FENDER ORNAMENT

Perry E. Allen, Detroit, Mich.

Application August 20, 1952, Serial No. 21,137

Term of patent 7 years

(Cl. D14—6)

To all whom it may concern:

Be it known that I, Perry E. Allen, a citizen of the United States, residing in Detroit, county of Wayne, and State of Michigan, have invented a new, original, and ornamental Design for an Automobile Fender Ornament, of which the following is a specification, reference being had to the accompanying drawing, in which drawing:

Fig. 1 is a front elevational view of an automobile fender ornament, embodying my new design.

Fig. 2 is a side elevational view thereof.

Fig. 3 is a top edge view thereof.

I claim:

The ornamental design for an automobile fender ornament, as shown.

PERRY E. ALLEN.
